UNITED STATES PATENT OFFICE

WALTER C. STEWART, OF GASTONIA, NORTH CAROLINA, ASSIGNOR, BY MESNE ASSIGNMENTS, TO EMANUEL FROHMAN, OF GASTONIA, NORTH CAROLINA

DIFFERENTIAL MOTION FOR ROVING FRAMES AND THE LIKE

Application filed July 24, 1928. Serial No. 295,036.

My invention relates to a differential unit for roving frames, spinning frames and the like, in which means are provided for working in co-operation with the driving mechanism for the roving frame and varying the speed of the bobbin shafts.

An object of my invention is to provide a differential motion for roving frames by means of which the desired speed may be imparted to the bobbin shafts with the minimum amount of loss in energy in accomplishing this result.

Another object of my invention is to provide a differential motion for roving frames in which all of the moving parts move in the same direction at different speeds so as to procure the proper speed for the bobbin shafts with the minimum amount of power being wasted in attaining this result.

Some of the objects of my invention having been stated, other objects will appear as the description proceeds when taken in connection with the accompanying drawings, in which:—

Figure 1 is a side elevation of the portion of a roving frame showing my invention applied thereto;

Figure 2 is a longitudinal cross-sectional view taken along the line 2—2 in Figure 3.

Figure 3 is a cross-sectional view taken along the line 3—3 in Figure 2.

Referring more particularly to the drawings, the numeral 10 indicates the second samson of a roving frame, while the numeral 11 indicates the first samson of a roving frame and the numeral 12 indicates the head of the frame, and in the first and second samsons is mounted the shaft 13 on which the cone pulley 14 is mounted and also mounted on the shaft is the gear wheel 15 and pivotally mounted on the shaft is the arm 16 which has the gear wheel 17 pivotally mounted thereon, which gear wheel meshes with the gear wheel 15 and also the gear wheel 18 on the main drive shaft 19.

In the lower portion of the first and second samsons 10 and 11 is fixedly mounted the shaft 20, which has the pivoted arms 21 and 22 mounted thereon and in the ends of these arms is rotatably mounted the shaft 23 which

has the cone pulley 24 mounted thereon and running between the cone pulleys 14 and 24 is the cone belt 25 which has the cone belt rack or shifter 26 in engagement therewith for the purpose of guiding said belt on the cone pulleys. The shaft 20 has mounted thereon the gear 27, which gear engages the gear 28 fixedly mounted on the shaft 23, the gear 27 being integral with the sleeve 29 and on this sleeve 29 is mounted the gear 30, which gear engages in the gear 31 fixedly mounted on the shaft 32. It might be stated that the parts thus far described are the conventional parts of a roving frame in addition to some other parts hereinafter described, my invention as applied to roving frames being more specifically shown in Figures 2 and 3.

Fixedly mounted on the shaft 32 is the gear wheel 33, which is adapted to receive the chain belt 34 which chain belt 34 is also mounted on the gear 35 which is fixedly mounted on the sleeve 36 in the differential and this sleeve 36 has the gear teeth 37 integral therewith adapted to engage the pinions 38, 39 and 40, which pinions are mounted on the studs 41 which are fixedly secured to the disk 42, this disk 42 being fixedly mounted on the sleeve 43 by means of the set screw 44, and also if desired the wedge means 45 may be provided for securing the disk 42 on the sleeve 43. Fixedly mounted on the sleeve 43 by means of the set screw 46 and the slot and wedge means 47 is the gear wheel 48 which has the chain belt 49 mounted thereon, which chain belt is also mounted on the gear wheel 50 which is fixedly mounted on one of the bobbin shafts 51, said bobbin shaft having gear 52 thereon which is adapted to mesh with the gear 53 which is fixedly mounted on the other bobbin shaft 54. These bobbin shafts in Figure 1 are shown in elevated position, their proper position being immediately behind the roving frame differential, but they are lifted up for the sake of clearness.

The main drive shaft 19 has mounted thereon the loose pulley 55 and the tight pulley 56, which has integral therewith the hand wheel 57. This shaft 19 has fixedly mounted thereon the housing 58 by means of the set screw 59, said housing having the internal gear 60

around its entire periphery, which gear is adapted to engage the pinions 38, 39 and 40 which are mounted on the disk 42. The plate 61 is adapted to be secured to the housing 58 by means of the screws 62 and this plate 61 is adapted to fit around the sleeve 36 and have the felt washer 63 mounted therein to prevent the escape of the lubricant contained in the housing 58.

10 All of the parts having been described, the method of operation of my device is as follows:

Motion is imparted to the main drive shaft 19 in a clockwise direction looking from the 15 left hand end of Figures 1 and 2, for a clockwise direction looking at Figure 3. The housing 58 is driven in a clockwise direction or the upper portion of Figure 2 moves toward the observer and this housing 58 being 20 fixedly secured on the shaft 19 imparts rotary motion to the pinions 38, 39 and 40, which are mounted on the disk 42 which pinions being in engagement with the gear 37 on the sleeve 36 have a tendency to impart 25 a counter-clockwise movement to the sleeve 36 and the gear wheel 35 mounted thereon if the sleeve 43 and the disk 42 were to remain stationary. The drive shaft 19 having the gear 18 thereon moves the cone pulley 14 30 through the gear 17 in a clockwise direction which moves the belt 25 in the direction indicated by the arrow in Figure 1, it likewise imparts clockwise movement to the cone pulley 24 and the gear 28, which imparts counter-clockwise to the gears 27 and 30 which imparts clockwise movement to the gear 31, the shaft 32, the gear 33, the chain belt 34 and the gear 35 mounted on the sleeve 36, so it is seen that the housing 58 having the internal 35 gear 60 and the sleeve 36 having the gear 37 both move in a clockwise direction at different speeds, it being apparent that if they moved at the same speed that the pinions 38, 39 and 40 would remain stationary and 40 carry the disk 42 around at the same rate of speed at which the housing 58 and the sleeve 36 are moving, and would thus impart the same rate of speed to the gear 48, but due to the connection between the main drive shaft 19 through the gears 17, 15, the cone pulleys 45 14 and 24 and the gears 28, 27, 30, 31, 33, and 35, this sleeve 36 moves at a lesser rate of speed in a clockwise direction than the main shaft 19, and thus a braking effect is 50 imparted to the pinions 38, 39 and 40 and thus the speed of rotation of the plate 42, the sleeve 43 and the gear 48 which drives the bobbin shaft is retarded.

In the drawings and specification I have 60 set forth a preferred embodiment of my invention, and although specific terms are employed, they are used in a generic and descriptive sense only, and not for purposes of limitation, the scope of the invention being 65 set forth in the appended claims:

I claim:

1. In a differential unit for roving frames and the like, a driving shaft, a sealed housing having an internal gear fixedly mounted on the driving shaft, a sleeve mounted directly on the driving shaft for rotation thereon and having a disk secured thereto, a plurality of pinions mounted for rotation on the disk and being adapted to engage the said internal gear, a second sleeve mounted for 75 rotation on the first named sleeve and having a gear wheel thereon adapted to engage the said pinions.

2. In a differential unit for roving frames and the like, comprising a driving shaft, a sealed housing member having an internal gear therein and being fixedly mounted on the driving shaft, a sleeve rotatably mounted directly on the driving shaft and having a gear fixedly mounted thereon, a second sleeve 85 mounted on the first named sleeve and having a disk secured thereon, said disk being entirely within the sealed housing and enclosed thereby, said disk also having a plurality of pinions mounted thereon adapted 90 to engage the internal gear and also to engage the gear on the said sleeve.

3. In a differential motion for roving frames and the like, a main drive shaft, a housing member having an internal gear secured on the main drive shaft, a cover for said housing member fixedly mounted thereon, a sleeve rotatably mounted on the main drive shaft and having a portion thereof extending into the member having the internal gear, a disk secured to said sleeve, said disk being sealed in the casing, a plurality of pinions secured on the disk and being adapted to mesh with the internal gears on the said housing member, a second sleeve 100 member rotatably mounted on the first named sleeve member and having a gear thereon adapted to mesh with the said pinions, a gear wheel mounted on the first named sleeve, and a gear wheel mounted on the second named sleeve.

4. In a roving frame and the like having a main drive shaft, a hollow circular casing fixedly secured on the drive shaft, and having a bottom member integral therewith, a 115 cover member fixedly secured on the casing, said cover member having a hole in its center, an internal gear on the periphery of said casing, a sleeve rotatably mounted directly on the drive shaft and having a major portion thereof on the outside of the casing with one of its ends projecting into the casing, a disk fixedly mounted on the ends of the said sleeve in the housing, pinions on said sleeve adapted to mesh with the said internal gear, a 125 gear wheel on the exterior end of said sleeve, a second sleeve rotatably mounted on the said first sleeve and having one end thereof projecting through the hole in said cover into the casing forming a close fit in said hole, 130

and having a spur gear on the end within the casing, which is adapted to mesh with said pinions, and a gear mounted on the portion of said second sleeve outside of the casing.

In testimony whereof I affix my signature.

WALTER C. STEWART.
